(57) **CLAIM**

The ornamental design for a wall-mount valve-operating assembly, as shown.

DESCRIPTION

FIG. 1 is a perspective view of the wall-mount valve-operating assembly according to the invention;

FIG. 2 is a left-side elevation, the right side being a mirror image thereof;

FIG. 3 is a top plan view thereof;

FIG. 4 is a front-elevation thereof;

FIG. 5 is a rear-elevation thereof; and,

FIG. 6 is a bottom plan views thereof.

The broken circumferential lines shown in FIG. 5 define the unclaimed bounds of the design and form no part thereof.
